(57) CLAIM

The ornamental design for a vase, as shown and described.

DESCRIPTION

FIG. 1 is a front elevation view of a vase showing my new design;

FIG. 2 is a front perspective view thereof;

FIG. 3 is a back perspective view thereof;

FIG. 4 is a back elevation view thereof;

FIG. 5 is a left side elevation view thereof;

FIG. 6 is a top plan view thereof; and,

FIG. 7 is a right side perspective view thereof.

The broken lines in FIGS. 2, 3, 6 and 7 define the bounds of the claimed design and form no part thereof.
